UNITED STATES PATENT OFFICE

XAVIER LAUCIRICA, OF NEW YORK, N. Y.

STUFFING MATERIAL

Application filed June 21, 1929. Serial No. 372,724.

This invention relates to new and useful improvements in materials for stuffing mattresses, pillows, cushions, furniture seats, and other similar objects.

The invention has for an object the provision of material of the class mentioned which is of simple durable construction, dependable in use and efficient in action, and which may be manufactured and sold at a reasonable cost.

The invention proposes the use of pieces of cork formed in strips or small pieces of sheets, of onion skin weight and haphazardly crumpled and wrinkled into mass form for providing stuffing material. In this specification the term "mass form" is meant to be the form obtained by crumpling and wrinkling the sheet so that many overlapping folds occur. This particularly distinguishes from the mere crumpling and wrinkling of a sheet which is thereafter again flattened out into sheet form and simply presents the creases caused by the wrinkling. The term "mass form" in this specification means the form in which the sheet is before it is again straightened out. In this condition of the material, it has quite elastic properties and will not clog or become hard. In addition it is very light and may keep in perfect condition for a very long period of time. This permits it to be substituted with greater advantages for other materials used up to date such as for wool, feathers, hair, etc. It is also proposed that the material may be rolled instead of being crumpled and wrinkled. A means may be provided for maintaining the rolled or crumpled condition of the individual pieces.

For further comprehension of the invention, and of the objects and advantages thereof, reference will be had to the following description and accompanying drawings, and to the appended claims in which

the various novel features of the invention are more particularly set forth.

In the accompanying drawings forming a material part of this disclosure:

Fig. 1 is a plan view of a piece of material in flat condition preparatory for use according to this invention.

Fig. 2 is an enlarged sectional view taken on the line 2-2 of Fig. 1.

Fig. 3 shows the sheet illustrated in Fig. 1 in a crumpled and wrinkled condition.

Fig. 4 is a side elevational view of Fig. 3.

Fig. 5 is a perspective view of the sheet shown in Fig. 1 in a rolled condition.

Fig. 6 is a plan view of a piece of the material constructed according to modified form.

Fig. 7 is a perspective view of the material shown in Fig. 6 in a rolled condition.

Fig. 8 is a perspective view of the material shown in Fig. 6 in a crumpled condition.

The reference numeral 10 indicates generally a strip or piece of dust of cork material, that is, in sheet form and of onion skin weight. Preferably the thickness of the sheet should be approximately one or two thousandths of an inch. Numeral 11 indicates the natural openings of the sheet 10 due to the apertures of a cork from which the sheet is cut. This thin material is quite soft and resilient. It is extremely flexible. It may be loosely crumpled and wrinkled in various haphazard forms and upon releasing will substantially maintain these forms. In this condition it is intended that the material be inserted as a filler for mattresses, pillows, cushions, furniture seats or other objects to be stuffed.

This material is very desirable for the purpose mentioned in that it maintains its fresh and resilient condition for quite some time. It does not clog or become hard easily, and in addition, since it is quite light, it is very desirable for stuffing. In Fig. 3 the sheet is shown in a crumpled and wrin-

kled condition. Fig. 4 merely illustrates the third dimensional view of Fig. 3.

The stuffing material may be modified by rolling the sheets of cork instead of crumpling and wrinkling them. Numeral 13 indicates the sheet shown in Fig. 1 in a rolled condition. A plurality of such rolls should be stuffed into the objects desired to be filled and quite a soft cushioning effect is produced by these rolls. These rolls when pressed together, as for example when someone sits upon a furniture seat stuffed with them, they become flattened out temporarily but offer quite some resiliency to being flattened out. When the person leaves the seat the rolls immediately expand to substantially their original conditions. This is quite desirable. In the event that the rolls are used in pillows, the pillows may be manually handled for conditioning them into a puffed form.

In Fig. 6 a modified form has been illustrated in which sheet cork material 10 has plastic material 14 such as shellac engaged along its longitudinal edges. In Fig. 7 the sheet illustrated in Fig. 6 is in rolled condition so that the plastic material 14 is at the ends of the roll. The plastic material tends to maintain the rolled condition of the sheet and the material intermediate the plastic edges retains all of its previous resilient and soft qualities. The material shown in Fig. 6 may also be crumpled and wrinkled as shown in Fig. 8. The plastic portions of this material tend to maintain its shape in crumpled condition while the remaining portion of the material presents the resilient and soft qualities.

Very thin sheets of cork are very soft and have quite elastic qualities. When these sheets are crumpled into mass form, they produce a mass which is very soft and resembles in certain characteristics feathers very closely. The crumpling of thin cork sheets into the mass form is substantially different than the mere crumpling of paper sheets and distinctly different from crumpled paper sheets which have thereafter been flattened out again. The difference is that the structural quality of the different materials are such that a much softer mass is obtained by the use of the cork sheets.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. Material for the stuffing of mattresses and other similar objects, comprising pieces

of cork in the form of thin wrinkled strips, and shellac on the longitudinal edges of said pieces.

2. Material for the stuffing of pillows, furniture seats and the like, comprising pieces of sheet cork of onion skin weight and crumpled and wrinkled, and plastic material on the longitudinal edges of the pieces.

In testimony whereof I have affixed my signature.

XAVIER LAUCIRICA.
